UNITED STATES PATENT OFFICE.

BERNHARDT JORGENSEN, OF BEVERLY, MASSACHUSETTS, ASSIGNOR TO UNITED SHOE MACHINERY CORPORATION, OF PATERSON, NEW JERSEY, A CORPORATION OF NEW JERSEY.

TRIMMING MACHINE.

Application filed January 10, 1924. Serial No. 685,381.

This invention relates to trimming machines and more particularly to machines for trimming surplus material from the bottom of a lasted shoe.

5 A well-known type of sport shoe has a canvas upper and a rubber sole, and depends upon a vulcanizing operation to attach the sole. Incidentally to lasting such a shoe the marginal portion of the canvas upper is drawn over the edge of the insole and is secured to the bottom of the latter by an adhesive. The insole, in a shoe of this type, is smooth and without the channel, lip and shoulder commonly provided in insoles for 10 other types of shoes, but notwithstanding this condition lumps are produced in the overdrawn marginal portion of the upper around the toe where it is necessary to crimp or pleat the upper to effect satisfactory lasting. It becomes necessary to trim the crimped or pleated portions to make the bottom of the lasted shoe smooth and even before the outsole is laid, for otherwise they would seriously weaken the union to be subsequently effected by vulcanization and 15 would impart unevenness to the outsole.

The accompany drawings illustrate an improved trimming machine suitable for trimming the crimped or pleated portions that 20 have been formed on the bottom of a lasted shoe, and for trimming off lumps of any form, however they may have been produced. The invention is not, however, restricted to the particular operation or to the 25 type of shoe mentioned, but since the illustrated construction is designed for said operation it will be described accordingly.

An object of the invention is to provide 30 a trimming machine by which the trimming will be caused to conform to the transverse convexity and the longitudinal convexity or spring of the bottom of the shoe. To this end, a feature of the invention consists in regulatable cutting means the effective 35 shape of which is variable at the cutting locality to approximate a curvature of the work, for example, the transverse convexity of the shoe bottom. The preferred type of cutting means comprises rotary disk knives 40 arranged in edge-to-edge relation and relatively adjustable to various angular relations so that their cuts, considered collectively, will approximate the transverse curvature of the work.

Another feature of the invention comprises improved means for controlling manipulation of the shoe to insure trimming in a predetermined course or courses without especial skill on the part of the operative. The illustrated means for this purpose are 45 constructed and arranged to engage the bottom of the shoe to steady the latter against rocking sidewise and to lead the shoe so that the course or courses of trimming will be parallel to the longitudinal curvature or 50 spring of the shoe bottom.

One novel feature of the work-guiding means consists in a work-rest movable with the work to lead the toe end into operative 55 relation with the trimming means and guided to impart a longitudinal rocking movement to the shoe such as to cause the trimming to progress parallel to the spring of the shoe bottom.

Still another feature consists in improved 60 means for covering the trimming means to guard the operative's fingers from injury. This feature includes movable guards initially covering the cutting edges of the knives, and means movable by the work to 65 retract said guards from the path of the work. The aforesaid movable work-rest may be caused to do double duty by using it to retract the above-mentioned guards, and it is arranged and connected to be so 70 used in the organization herein disclosed.

The trimming knives are not only relatively adjustable, as hereinbefore explained, to conform to the transverse curvature of the work, but are also preferably adjustable 75 bodily toward and from one another to compensate for diminutions in diameter as they become worn by grinding. In view of these conditions of adjustability another novel 80 feature of the invention consists in improved mechanism for operating the trimming knives, which mechanism is organized to partake of the various adjustments of the knives so that the desired operating connection will be maintained under all 85 conditions.

The illustrated organization also includes 90 grinding members for sharpening the trimming knives respectively, and a novel feature concerning them consists in their arrangement by which they are caused to 95 partake of the various adjustments imparted to the trimming knives, whereby the desired 100 105 110

relation between the knives and their respective grinders will be maintained under all conditions and not disturbed by adjusting the knives.

5 Referring to the drawings,

Fig. 1 is a front elevation partly in section of mechanism embodying this invention in a preferred form, the view including the working head, but not the base or frame, of a trimming machine;

10 Fig. 2 is a side elevation of the mechanism shown by Fig. 1 as viewed from right to left, the front being at the left;

15 Fig. 3 is a perspective view of the working head, parts of which are broken away to show certain features of construction;

20 Fig. 4 is a side elevation representing various positions of the work and the movable work-rest, the direction of view being from left to right with reference to Fig. 1;

25 Fig. 5 is a diagrammatic plan view including the two cutters, the toe portion of a shoe in four successive positions, and one of the work-engaging abutments of the movable work-rest in successive positions corresponding to those of the shoe;

30 Fig. 6 is a view partly in vertical section and partly in front elevation showing the angular relation of the knives by which the trimming cut is shaped to conform approximately to the transverse convexity of the shoe bottom; and

35 Fig. 7 is a perspective view showing an arrangement of pulleys by which a single belt may rotate the two knives in opposite directions.

40 The two trimming knives 10, 10 are carried by rotary shafts 11 journaled in members 12. Pulleys 13 are fastened to the shafts to be driven preferably in opposite directions by any suitable means such as a belt 14. Fig. 7 shows a convenient arrangement of pulleys by which rotation may be transmitted to both shafts 11 by a single belt receiving power from a driving pulley 15. This transmission means includes also two idle pulleys 16 and an idle pulley 17 arranged upon an eccentric collar 18 fastened to a stud 19. A head 20 fastened to the stud 19 provides a handle by which the stud may be turned to regulate the tension on the belt. Any suitable means such as a set screw arranged to engage the stud may be provided to maintain the desired position of adjustment.

45 The journal members 12, 12 are carried by horizontally adjustable supporting members 21, 21 and are connected to said supporting members by pivots 22 and by clamping bolts 23. The pivots 22 provide for angular adjustment of the knives which, as shown by Fig. 1, are in edge-to-edge relation and at an angle conforming substantially to the transverse convexity of a shoe bottom. The clamping bolts 23 extend

through curved slots or notches in the journal members 12 and are screwed into the supporting members 21. This connection affords a considerable range of adjustment of the journal members about their respective pivots 22.

50 The supporting members 21 are provided with dovetail portions arranged to slide in a dovetail guideway 24 formed in a head portion 25 of the frame. A screw shaft 75 having right and left screw portions 26 and 27 extends through the supporting members 21 and cooperates with internal threads to adjust said members in unison toward and from each other. Endwise movement of the 80 screw shaft is prevented by collars 28 arranged to engage opposite faces of a stationary bracket 29 through which the middle portion of the shaft extends. The shaft is provided with a knob 30 by which to turn 85 it. This adjusting means provides for taking up clearance between the cutting knives as the latter become reduced in diameter by sharpening.

85 To protect the operative's fingers from touching the knives the mechanism is provided with stationary guards 31, 31 and movable guards 32, 32, the stationary guards being arranged to cover the outer portions of the knives while the movable guards are 95 arranged to cover the forward portions, that is, the portions toward the operative. The stationary guards are provided with split hub portions 33 arranged to surround and clamp the lower portions of the journal members 12. Each of these hub portions is provided with a screw for producing the clamping action.

100 The movable guards 32 are movable to and from their protecting positions, and stand initially in positions to cover the knives but are automatically retracted from said positions by mechanism hereinafter described to enable the knives to function when a shoe is presented to them for trimming. Each movable guard is connected to the corresponding stationary guard by a pivot member 34 and therefore partakes of whatever adjustment is imparted to the corresponding knife.

110 To avoid the necessity of removing or disturbing the knives for sharpening, the mechanism is provided with grinding devices arranged to operate on the knives while the latter are in their operative positions. Moreover, these grinding devices are arranged to partake of the various adjusting movements of their respective knives to maintain the desired potential grinding relation. Each grinding device comprises a wheel or disk 120 35 of abrading material, the periphery thereof being arranged to operate on the knife. The grinding disk is fixed to a stud shaft journaled in a bracket 36. The bracket is clamped to a holder 37 by a screw 38 that 130

provides for angular adjustment of the bracket to adjust the tangent portion of the grinding disk crosswise of the edge of the cutter. The holder 37 is arranged to slide 5 up and down in a bearing formed in the journal member 12 to move the grinding disk toward and from the knife. For this purpose an adjusting screw 39 is screwed into the upper end of the holder and is provided with a knob 40 by which to turn it. A bracket 41 fixed to the journal member occupies a groove 42 in the screw member to prevent the latter from moving endwise.

The relation of the grinding disk to the 15 knife is such that when they are in contact with each other the knife rotates the grinder, and no additional means is required to effect such rotation. The cutting edge of the knife moves diagonally across the periphery of 20 the grinder at an angle that is sufficient to impart rapid rotation to the grinder. The grinding effect is therefore produced partly by the rotative movement of the knife and partly by rotative movement of the grinder. 25 In practice the grinder will be normally maintained out of contact with the knife and will be depressed to engage the knife only when the latter requires sharpening.

To use the machine for trimming the bottom 30 of a shoe the operative holds the shoe in both hands bottom up and with the toe pointed toward the tangent of the cutting knives, and then moves the shoe longitudinally into contact with the knives so that 35 one of the latter will trim one side of the toe while the other trims the other side. To do satisfactory work it is necessary to regulate the closeness of trimming with precision, and this requires not only determining 40 the level of that portion of the work that first comes in contact with the knives but also the angle of the shoe with respect to the longitudinal curvature or spring of the bottom. It is also necessary to control the 45 position of the shoe with respect to rocking sidewise to insure uniform closeness of trimming by the two knives.

Accordingly the invention provides various work-engaging elements constructed and 50 arranged to control manipulation of the shoe so that the trimming will be uniform and accurate and so that it may be performed rapidly. These elements include a three-point work-rest arranged to move with the 55 work toward and from the trimming locality and adapted to counteract sidewise tipping of the work and to impart such longitudinal tipping as may be necessary to cause the trimming to progress in courses parallel to 60 the longitudinal curvature or spring of the shoe bottom. The said three-point work-rest includes a leading abutment 45 and two trailing abutments 46, 46. The abutment 45 is arranged to contact the insole 47 adjacent to the toe end of the shoe while the

abutments 46 are arranged to contact the overdrawn marginal portion 48 of the upper at or near the ball portion. The abutments 46 are preferably in the form of sharp spurs to pierce the bottom of the shoe so that the latter will not slip or twist relatively to them. They are preferably carried by a thumb-guard 50 arranged to extend across the shoe and preferably of a length greater than the width of the shoe and greater than the gap 70 between the forward edges of the stationary knife guards 31. The guard 50 is adapted to safeguard the operative's thumb from touching the exposed portions of the knife when the shoe is moving toward the latter. 75 In practice it will be convenient for the operative to grasp the heel end of the shoe with one hand and the instep portion with the other hand with the fingers of the latter hand under the instep portion and the thumb on the shoe bottom and in front of the guard 50, that is to say, with the guard between the thumb and the knives. Having raised the shoe to engage the abutments 45, 46, 46, as shown by Fig. 3, but with enough 80 pressure to cause the abutments 46, 46 to pierce the work, the operative has merely to advance the shoe, toe foremost, while maintaining sufficient upward pressure to keep it in contact with the three abutments. As 85 the shoe advances it carries the guiding abutments toward the knives, the movable knife guards 32 are automatically lifted to uncover the working portions of the knives, and the three-point work-rest controls the 90 course of the shoe so that the toe will clear and pass under the knives while the abutments 46 counteract any tendency of the shoe to tip sidewise. The guard 50 may advance until its tips are arrested by contact with 95 the stationary knife guards 31, and if the operative's thumb is in front of the guard 50 it is protected from injury by the knife. 100

The abutment 45 is a relatively thin or narrow portion of a link 51 to which the guard 50 is fastened by a clamping screw 52. A shank portion formed on the guard is arranged between two confronting flanges 53 of the link. The clamping screw 52 extends through a slot 54 in the guard and 105 is screwed into the link, the slot affording a range of vertical adjustment of the abutments 46 relatively to the abutment 45 to adapt the work-rest to shoes having various degrees of spring. 110

The path of movement of the abutment 45 is controlled by a pendular link 55 while the paths of movement of the abutments 46 are controlled by a cam slot 56. The link 55 is suspended by a pivot member 57 fastened to the bracket 29, the lower end of said link being connected to the abutment 45 by a pivot member 58. The abutment 45 swings in an arc the center of which is so located that the abutment reaches its low- 115

est position when about midway between the two limits of its range of movement and a short distance in front of the tangent of the knives. Consequently, as the abutment 5 progresses from its lowest plane to its most advanced position it rises to clear and pass over the tangent of the knives as shown by Figs. 4 and 5.

The duty of the abutment 45 is to lead the toe end of the shoe under the knives, and having done so it has no further duty to perform although it has a considerable range of movement thereafter as the shoe continues to advance. The abutments 46, however, remain in engagement with the shoe throughout the entire range of travel and not only continue to counteract any tendency of the shoe to rock sidewise but they traverse irregular paths produced by the cam 56 to control longitudinal rocking of the shoe so that the courses of trimming will conform substantially to the spring of the shoe bottom.

The upper end of the link 51 is forked to straddle the portion of the bracket 29 in which the cam 56 is formed, and to receive a roller 59 which travels in the cam slot. A tension spring 60 anchored to a hook 61 and connected to the link 55 maintains the work-rest initially in the position shown by Figs 2, 3 and 4. The shape of the cam is such that the abutments 46 move initially in substantially rectilinear and horizontal paths while the abutment 45 has a component of downward movement sufficient to lead the toe of the shoe under the knives; and about the time the toe of the shoe begins to move under the knives the cam 56 gives the abutments 46 a component of upward movement.

Fig. 5 illustrates diagrammatically successive positions of the toe of the shoe in relation to the knives 10, and includes conventional representation of the abutment 45 in successive positions corresponding to those of the shoe. A condition shown by this figure is that operative relation between the shoe and the knives begins simultaneously at points 62, 62 and progresses in opposite directions from each of the said points so that the cuts made by the two knives become merged with each other at the extreme tip of the toe while they progress also toward the other end of the shoe. The folds, crimps or plaits 63 formed in the overdrawn marginal portion of the upper incidentally to lasting are trimmed off flush with the relatively flat portion of the upper that lies in contact with the insole, the drawing cuts executed by the knives and the angular relation of the knives approximating the transverse convexity of the shoe bottom both contributing to make close trimming possible. If any up or down adjustment of the abutment 45 is necessary to

regulate the closeness of trimming it may be produced by turning the eccentric pivot member 57 on which the link 55 is suspended.

As shown by Fig. 1 the eccentric pivot member 57 is provided with a shank portion 64 that extends through and has bearing in the bracket 29. It is provided with a crank 65 by which to turn it. A screw 66 extends through the crank and is provided with a nut 67 which serves as a knob by which to turn the crank and which also serves to clamp the crank at any position at which it may be left. A head 68 formed on the screw 66 is arranged to travel in a T-slot 69 formed in a fixture 70. The head 68 and nut 67 cooperate to clamp the crank against the fixture 70.

Referring to the movement of the three-point work-rest, since the toe end of the shoe advances under the knives while the abutment 45 passes over the knives, and since the shoe is therefore deprived of the guiding effect of the abutment 45 before the shoe has completed its movement, the invention provides supplemental guiding means arranged to cooperate with the abutments 46 during that period when the shoe is deprived of the guiding effect of the abutment 45. The preferred guiding means for this purpose are shown by Fig. 6 and comprise thin plates or shields 71, 71 arranged under and in contiguous relation to the knives. These shields are circular and are arranged in concentric relation to the knives respectively. In diameter they are slightly smaller than the knives and it is therefore necessary for the edge of the shoe to move into lapped relation with the knives before it can engage these shields.

It follows, therefore, that only the trimmed portions of the work, or at least those portions that have passed the trimming locality, ever engage the shields 71, all surplus material having been trimmed from those portions that are advanced far enough to engage the shields. The shields are preferably very thin at their rims to permit the desired closeness of trimming, and graduated in thickness toward the centers. They are mounted to partake of the various adjustments of which the knives are capable, and consequently they too are adapted to be adjusted at an angle relatively to each other to conform approximately to the transverse convexity of the shoe bottom as shown by Fig. 6.

Since shoes of the type hereinbefore described are sticky on the bottom in consequence of the use of adhesive substance to hold the overdrawn marginal portion of the upper, the tendency of the adhesive to retard the movement of the work may be avoided by arranging the shields to rotate. As shown by the sectional construction in

Fig. 6, each shield is fastened to a stem 72 and the latter is journaled in a bushing 73 inserted into the shaft 11. A head 74 secured on the inner end of the stem confines the latter in the bushing while the bushing is confined by lapped relation with the body of the knife. The screws 75 which fasten the knife to the shaft thus serve to maintain the assemblage intact while the shield and the stem are free to turn in response to the frictional demands of the work engaging the shield.

It has been stated that the working portions of the knives are initially covered by the movable guards 32 and that the latter are automatically retracted to expose the knives when a shoe is advanced to the trimming locality. The mechanism for effecting retraction of the guards 32 is arranged to be operated by the three-point work-rest, or, more specifically, by the link 55 forming a part of said work-rest. As shown by Figs. 2, 3 and 4, a link 76 is pivotally connected to the link 55 and to a lever 77. This lever is connected to the bracket 29 by a fulcrum member 78 and is arranged to act against the under surface of a lever 79 which is also connected to the bracket 29 by a fulcrum member 80. A link 81 pivotally connected to the free end of the lever 79 is suspended so that its lower end hangs between the movable guards 32. A pin 82 is rigidly fastened to the lower end of the link and projects in opposite directions therefrom to engage the guards 32, the guards having holes 83 through which the ends of the pin project. This mechanism is so organized that the three-point work-rest, in moving toward the trimming locality, causes the lever 77 to raise the lever 79 and with it the guards 32. This lifting of the guards occurs during the first stages of movement of the three-point work-rest and uncovers the working portions of the knives before the toe of the shoe has reached the trimming locality. To avoid further upward movement of the guards 32 after they have risen far enough to afford access to the knives the lever 79 is provided with a curved notch or recess 85 in which the effective portion of the lever 77 may travel without causing movement of the lever 79.

Since the guards 32 partake of the various adjustments of the knives toward and from each other and otherwise to vary their angular relation, and since the link 81 for raising the guards does not partake of such adjusting movements the holes 83 through which the pin 82 extends are preferably made large enough to provide for such adjustments without producing binding of the pin in the holes, the pin being long enough to maintain connection with the guards when the latter are as far apart as it is ever

necessary to separate them. Each guard 32 is provided with an ear 86 at its free end to rest on the corresponding stationary guard 31 when the movable guard is in its lowest position.

Having thus described my invention, what I claim as new and desire to secure by Letters Patent of the United States is:

1. A machine of the character described comprising cutting means arranged to trim surplus material projecting from a convex surface, said means being regulatable whereby its effective shape is variable and approximately conformable to the convexity of said surface.

2. A machine of the character described comprising rotary cutting means arranged to trim surplus material lying on and projecting from a surface of an article of work, and adjustable means arranged to conform the effective shape of said cutting means approximately to a curvature of such surface.

3. A machine of the character described comprising a plurality of rotary power-driven disk knives arranged out of contact with each other to operate individually but simultaneously on the bottom of a lasted shoe to trim surplus material therefrom.

4. A machine of the character described comprising a plurality of rotary power-driven disk knives arranged to function in edge-to-edge relation to trim surplus material from the bottom of a lasted shoe, said knives being relatively adjustable to conform collectively to the transverse curvature of the shoe bottom.

5. A machine of the character described comprising two angularly adjustable rotary disk knives arranged to operate in edge-to-edge relation to trim surplus material from the bottom of the toe and sides of a shoe.

6. A machine of the character described comprising two rotary power-driven disk knives arranged to function simultaneously but individually one to trim surplus material lying on the margin of the bottom of a lasted shoe while the other trims surplus material lying elsewhere on said margin.

7. A machine of the character described comprising two rotary disk knives arranged to trim surplus material from the bottom of the toe and sides of a lasted shoe, said knives being relatively adjustable to conform the angle of their cutting edges approximately to the convexity of the shoe bottom.

8. A machine of the character described comprising cutting means arranged to trim surplus material from the bottom of a lasted shoe presented toe foremost thereto, and guiding means arranged to be engaged and moved toward said cutting means by the bottom of the shoe, said guiding means being constrained to supplement the longi-

- tudinal movement of the shoe with a component of other movement to cause the trimming to proceed along a curvilinear course substantially parallel to the longitudinal curvature of the shoe bottom.
9. A machine of the character described comprising cutting means adapted to trim surplus material from the bottom of a lasted shoe, and means including bodily movable abutments arranged to engage the bottom of the shoe at three separate points to control manipulation with respect to rocking while the shoe is undergoing trimming by said cutting means.
10. A machine of the character described comprising cutting means adapted to trim surplus material from the bottom of a lasted shoe, three bodily movable abutments constructed and arranged to have separate points of contact simultaneously with the bottom of the shoe, and means for giving two of said abutments dissimilar components of movement to control manipulation of the shoe during the trimming thereof.
11. A machine of the character described comprising cutting means adapted to trim surplus material from the bottom of a lasted shoe, and means including a bodily movable work-rest arranged to counteract sidewise rocking and to produce lengthwise rocking of the shoe so that the course of trimming will curve according to the longitudinal curvature of the shoe bottom.
12. A machine of the character described comprising two rotary disk knives arranged to trim surplus material from the bottom of a lasted shoe and arranged at an angle conforming substantially to the transverse convexity of the shoe bottom, and means constructed and arranged to control longitudinal motion of the shoe so that the trimming cuts of said knives will follow courses substantially parallel to the spring of the shoe bottom.
13. A machine of the character described comprising trimming means including two oppositely driven rotary disk knives for executing drawing cuts simultaneously to trim surplus material from opposite margins of the bottom of a lasted shoe, and means constructed and arranged to control manipulation of the shoe so that the trimming cuts of said knives will follow courses substantially parallel to the spring of the shoe bottom.
14. A machine of the character described comprising trimming means constructed and arranged to execute two drawing cuts simultaneously to trim surplus material from opposite margins of the bottom of a lasted shoe, said means being arranged to make said cuts at an angle conforming substantially to the transverse convexity of the shoe bottom, and means for controlling longitudinal movement of the shoe so that said cuts will follow courses substantially parallel to the spring of the shoe bottom.
15. A machine of the character described comprising cutting means adapted to trim surplus material from the bottom of the toe of a lasted shoe, stationary guards arranged adjacent to said knives respectively and behind their cutting edges to engage the trimmed portion of the shoe, and movable means constructed and arranged to determine the closeness of trimming before the trimmed portion reaches said guards.
16. A machine of the character described comprising cutting means adapted to trim surplus material from the bottom of the toe of a lasted shoe, stationary guards arranged adjacent to said knives respectively and behind their cutting edges to engage the trimmed portion of the shoe, and movable means constructed and arranged to determine the closeness of trimming before the trimmed portion reaches said guards.
17. A machine of the character described comprising cutting means adapted to trim surplus material from the bottom of a lasted shoe, and a movable work-rest comprising three separate abutments arranged to engage the shoe bottom and one of them being formed to pierce the shoe bottom to obtain a hold thereon, said abutments being adapted to control manipulation of the shoe with respect to rocking sidewise and lengthwise.
18. A machine of the character described comprising cutting means adapted to trim surplus material from the bottom of a lasted shoe, and a movable work-rest comprising three separate abutments arranged to engage the shoe bottom in triangular relation, two of said abutments being formed to pierce the shoe to prevent twisting or skewing thereof while all three of them are effective to control the shoe with respect to rocking.
19. A machine of the character described comprising cutting means adapted to trim surplus material from the bottom of a lasted shoe, a movable guard constructed and arranged to extend across the shoe bottom between the operative's point of grasp and said cutting means, and means for guiding said guard toward and from the cutting means.
20. A machine of the character described comprising cutting means adapted to trim surplus material from the bottom of a lasted shoe, a movable guard constructed and arranged to extend across the shoe bottom between the operative's point of grasp and said cutting means, means for guiding said guard toward and from said cutting means, and a sharp spur carried by said guard to pierce the shoe bottom so that the guard will be moved toward said cutting means by the shoe.
21. A machine of the character described comprising cutting means adapted to trim surplus material from the bottom of a lasted shoe, stationary means arranged to cover opposite sides of said cutting means to prevent

injury to the operative but having a gap to admit the work to be trimmed, a guard constructed and arranged to extend across the shoe bottom and to move with the shoe, and means for guiding said guard toward the trimming locality, said guard being adapted to bridge said gap and to be arrested by engagement with said stationary means.

22. A machine of the character described comprising cutting means adapted to trim surplus material from the bottom of a lasted shoe, a movable guard constructed and arranged to extend across the bottom of a lasted shoe between the operative's point of grasp and said cutting means, means for guiding said guard toward and from said cutting means, and means carried by said guard to prevent twisting or skewing motion of the shoe.

23. A machine of the character described comprising cutting means adapted to trim surplus material from the bottom of a lasted shoe, a movable guard constructed and arranged to extend across the bottom of a lasted shoe between the operative's point of grasp and said cutting means, means for guiding said guard toward and from said cutting means, and means carried by said guard to prevent twisting and sidewise rocking of the shoe.

24. A trimming machine comprising two cooperative rotary disk knives arranged in edge-to-edge relation to trim surplus material from the bottom of a lasted shoe, and a movable work-rest comprising three separate abutments arranged to engage the shoe bottom, two of said abutments being arranged to engage the shoe substantially abreast of each other to counteract sidewise rocking while the other is arranged nearer the knives and in register with the substantially tangential point of their cutting edges.

25. A machine of the character described comprising cutting means adapted to trim surplus material from the bottom of a lasted shoe, and a movable work-rest arranged to impart to the shoe a component of lengthwise rocking as the shoe is moved lengthwise in operative relation to said cutting means, to guide the trimming cut along a course substantially parallel to the longitudinal curvature of the shoe bottom.

26. A machine of the character described comprising cutting means adapted to trim surplus material from the bottom of a lasted shoe, a movable work-engaging member arranged to pass and clear the cutting edge to guide the toe end of the shoe to the latter, and movable work-engaging means arranged to cooperate with said member to guide the shoe and control it with respect to rocking.

27. A machine of the character described comprising cutting means adapted to trim surplus material from the bottom of a lasted shoe, a movable work-engaging member ar-

ranged to pass and clear the cutting edge to guide the toe end of the shoe to the latter, movable work-engaging means arranged to cooperate with said member to guide the shoe, and means behind the cutting edge to 70 guide the shoe by engagement with the portion that has passed said edge.

28. A machine of the character described comprising cutting means adapted to trim surplus material from the bottom of a lasted shoe, a work-engaging member arranged to swing about an axis to guide the toe end of the shoe to said cutting means, said member being arranged also to pass and clear the cutting edge, other work-engaging means so coupled to said member to move in unison therewith, and means for guiding said other means to produce a component of movement whereby the trimming is caused to parallel the spring of the shoe bottom.

29. A machine of the character described comprising cutting means adapted to trim surplus material from the bottom of a lasted shoe, a work-engaging member arranged to swing about an axis to guide the toe end of the last to said cutting means, and other work-guiding means including a link pivotally connected to said member to move in unison therewith, work-engaging abutments carried by said link, and a cam for guiding said link to produce a component of movement whereby the trimming is caused to parallel the spring of the last.

30. A machine of the character described comprising cutting means adapted to trim surplus material from the bottom of a lasted shoe, and work-guiding means comprising a plurality of work-engaging abutments coupled to move in unison and guided to follow curved paths for guiding the course of trimming substantially parallel to the spring of the shoe bottom.

31. A machine of the character described comprising cutting means adapted to trim surplus material from the bottom of a lasted shoe, and work-guiding means comprising a plurality of work-engaging abutments movable in unison with the shoe and guided to curve the course of trimming substantially to parallel the spring of the shoe bottom.

32. A machine of the character described comprising cutting means adapted to trim surplus material from the bottom of a lasted shoe, a work-engaging abutment movable in an arc to guide the toe end of the shoe to said cutting means, and other work-engaging means for guiding the shoe so that the course of trimming will parallel the spring of the shoe bottom.

33. A machine of the character described comprising cutting means adapted to trim surplus material from the bottom of a lasted shoe, and work-guiding means including a plurality of work-engaging abutments movable in unison but having dissimilar paths of

movement for guiding the shoe so that the course of trimming will parallel the spring of the shoe bottom.

34. A machine of the character described comprising rotary twin disk knives arranged in edge-to-edge relation to trim surplus material from the bottom of a lasted shoe, shafts by which said knives are carried, and work-guiding means including three movable work-engaging abutments coupled to move in unison, one of said abutments being arranged to guide the toe end to said knives and thereafter pass between said shafts while two others are arranged to engage the bottom 15 of the shoe nearer the heel end.

35. A machine of the character described comprising rotary twin disk knives arranged in edge-to-edge relation to trim surplus material from the bottom of a lasted shoe, and work-guiding means including three movable abutments arranged to engage the bottom of the shoe in triangular relation, one of said abutments being in advance of the others and arranged to guide the toe end of 20 the shoe to said knives and then to pass between the cutting edges of the knives to clear the latter.

36. A machine of the character described comprising a knife formed and operated to execute a drawing cut and arranged to trim lumps from the overdrawn marginal portion of an upper on the bottom of a lasted shoe, a thin shield arranged in confronting relation to the body of said knife to engage the 30 trimmed part of the work, the cutting edge of said knife being in front of the front edge of said shield, and movable work-engaging means constructed and arranged to guide the work to said knife and to cooperate with 35 said shield to control the course of trimming.

37. A machine of the character described comprising cutting means adapted to trim surplus material from the bottom of a lasted shoe held in the hands, movable means arranged initially to cover said cutting means, and means movable by the shoe to retract 40 said covering means from said cutting means.

38. A machine of the character described comprising relatively adjustable cutters arranged to operate simultaneously on a shoe, movable guards arranged to stand initially in front of said cutters respectively and in the path of the work, said guards being arranged to partake of relative adjustment of 50 said cutters, and means arranged to be moved by the work to retract said guards from the path of the work.

39. A machine of the character described comprising a plurality of disk knives arranged to trim surplus material from the bottom of a lasted shoe, said knives being adjustable relatively to each other, stationary guards arranged to cover portions of 55

said knives respectively and to partake of 60 adjustments of their respective knives, movable guards arranged to cover other portions of said knives respectively and to partake of 65 said adjustments, and means movable by the work to retract said movable guards and to maintain operative relation therewith while 70 the positions of the guards are being changed by adjusting said knives.

40. A machine of the character described comprising rotary twin disk knives arranged to trim surplus material from the bottom of a lasted shoe, said knives being relatively adjustable to various angles to approximate the transverse convexity of the shoe bottom, and shields arranged in contiguous relation 75 to said knives respectively to steady the shoe against rocking sidewise, said shields being arranged to partake of angular adjustments 80 of their respective knives.

41. A machine of the character described comprising rotary twin disk knives arranged 85 to trim surplus material from the bottom of a lasted shoe, shields arranged in contiguous relation to said knives respectively to guide the shoe by engagement with the trimmed portion of the bottom, a movable member arranged to engage the shoe bottom near the toe end to lead the latter to said shields, and 90 movable means arranged to engage the shoe bottom to cooperate first with said member and afterward with said shields to control 95 manipulation of the shoe.

42. A machine of the character described comprising a frame, a bearing member secured thereto, a shaft journaled in said bearing member, a disk knife carried by said 100 shaft, said bearing member being adjustable to tilt the axis of said knife, and a grinding disk carried by said bearing member to sharpen said knife and to partake of tilting adjustment thereof, said grinding disk being 105 also adjustable crosswise of the cutting edge of said knife.

43. A machine of the character described comprising a frame, supporting members mounted thereon to be adjustable toward and 110 from each other, journal members carried by said supporting members respectively and arranged to be adjustable to various angles relatively to said supporting members, rotary trimming knives journaled in said journal 115 members respectively to partake of angular adjustment of the latter and of adjustment of said supporting members, and grinding devices arranged to sharpen said knives respectively and mounted on said journal members 120 to partake of whatever adjustment is imparted to the knives.

In testimony whereof I have signed my name to this specification.

BERNHARDT JORGENSEN,
